(57) **CLAIM**

The ornamental design for a media player device as shown and described.

DESCRIPTION

FIG. 1 is a front elevation view of a media player device.

FIG. 2 is rear elevation view.

FIG. 3 is a top plan view.

FIG. 4 is a bottom plan view.

FIG. 5 is a left side view.

FIG. 6 is a right side view.

FIG. 7 is a perspective view; and,

FIG. 8 is a second perspective view.

The evenly broken lines show features of the media player device that form no part of the claimed design.

1 Claim, 7 Drawing Sheets
